Att'y.

UNITED STATES PATENT OFFICE.

FRANK MOORE, OF PITTSBURG, PENNSYLVANIA, ASSIGNOR TO THE WESTINGHOUSE AIR BRAKE COMPANY, OF SAME PLACE.

VALVE FOR FLUID-PRESSURE SIGNALING APPARATUS.

SPECIFICATION forming part of Letters Patent No. 453,604, dated June 2, 1891.

Application filed August 12, 1890. Serial No. 361,793. (No model.)

To all whom it may concern:

Be it known that I, FRANK MOORE, a citizen of the United States, residing at Pittsburgh, in the county of Allegheny and State of Pennsylvania, have invented or discovered certain new and useful Improvements in Valves for Fluid-Pressure Signaling Apparatus, of which improvement the following is a specification.

10 My present invention relates to and is an improvement upon apparatus for signaling by fluid-pressure of the type set forth in Letters Patent of the United States No. 435,783, granted and issued to The Westinghouse Air 15 Brake Company, of Pittsburgh, Pennsylvania, as assignee of Thomas W. Welsh, Francis L. Clark, and myself, under date of September 2, 1890, and its object is to further improve said apparatus by obviating the liability of the discharge-valve to be moved from its seat and undesired and improper signal-indications to be thereby given by the jolting and jarring of a car in passing over low joints or other defective portions of the track.

25 To this end my invention, generally stated, consists in the combination, with a casing having fluid-pressure supply and discharge passages, and a movable abutment working therein, of a discharge-valve connected to the movable abutment and having a face adapted to fit closely within the discharge-passage during the seating periods of the valve.

The improvement claimed is hereinafter 35 fully set forth.

The accompanying drawing is a vertical central section through a signaling-valve mechanism embodying my invention.

The apparatus in which my improvement 40 is herein exemplified, is in its general features of construction and operation similar to that of Letters Patent No. 435,783 aforesaid, and need not, therefore, saving as to the invention herein claimed, be again fully 45 and at length described. As in said application, the chamber or casing 1 is closed at top by a cap 2 and is divided by a movable abutment 5 into an upper compartment 6 and a lower compartment 7, of substantially larger 50 volume. A signaling-pipe connection or nozzle 8, for attachment to a pressure-supplying line, communicates by a small supply-pas-

sage 9 with the compartment 6, and a passage 10 leads from said compartment to a valve-chamber 11 below the compartment 7, from which chamber a discharge-passage 12 leads into a discharge nozzle or connection 13, adapted to be attached to a pipe leading to a signal-indicating device. The discharge-passage 12 is controlled by a discharge-valve 14 upon the lower end of a stem 15, secured to the abutment 5 and provided with lateral grooves or channels 17 for the passage of fluid from the compartment 7 to the valve-chamber and discharge-passage when the abutment and discharge-valve are raised by reduction of pressure in the supply-line.

In Letters Patent No. 435,783 aforesaid the discharge-valve 14 is in the form of a flat face upon the lower end of the stem 15 of the abutment and seats on a corresponding face around the upper end of the discharge-passage 12. Under such construction any upward movement, however slight, of the abutment coincidently separates the faces of the valve and seat and effects a discharge of fluid through the passage 12 to the signal-indicating device. Such separation of the discharge-valve and seat may in railroad service be accidentally effected by the jolting or jarring 80 of the car resultant upon passing over low joints or other imperfections and inequalities in the track, and a signal-indication be thereby improperly given, or a frequent repetition of faint or imperfect indications may be made 85 with annoying and disturbing effect upon the engineer.

In order to effectually obviate the above objection, I provide upon the lower end of the abutment-stem a discharge-valve 14, having, preferably, as in the patent aforesaid, a flat face adapted to seat upon a corresponding face surrounding the upper end of the discharge-passage 12 and provided with a cylindrical face formed upon a central projection extending a short distance into and fitting accurately in the discharge-passage, which passage will not, therefore, be opened to the valve-chamber 11 until the valve has been raised sufficiently far to completely 95 withdraw its projection from the discharge-passage. Such limited upward movement of the valve as might be due to jarring or jolting of the car, as before referred to, would 100

not, by reason of the provision of the projection, be sufficient to permit the escape of fluid into the discharge-passage, and would therefore have no objectionable effect, while on the other hand the normal operation of the valve in effecting discharge, when required, is in nowise impaired or limited.

A valvular appliance having a casing provided with fluid pressure and discharge pipes, a movable abutment, and a flat valve connected to the abutment and controlling communication between the supply and discharge pipes is set forth in Letters Patent No. 435,783, before referred to. Such construction I therefore distinctly disclaim as of my present invention.

I claim as my invention and desire to secure by Letters Patent—

The combination of a valve-casing, a fluid pressure-supply pipe opening directly thereto, a movable abutment fitted to work in the casing and normally subject to equilib-

rium of fluid-pressure on opposite sides, a discharge-passage leading from the casing, a valve-stem fixed to and movable with the abutment, and a discharge-valve fixed upon said stem and having a face adapted to seat upon a face at the opening of the discharge-passage, and a cylindrical projection fitting truly in said passage, said projection maintaining the normal closure of the passage during such limited movements of the abutment as may be due to shocks or jars and effecting the opening of the passage only in and by normal movement of the abutment due to variation of fluid-pressure on opposite sides thereof, substantially as set forth.

In testimony whereof I have hereunto set my hand.

FRANK MOORE.
